UNITED STATES PATENT OFFICE.

JAMES AUGUST BYINGTON, OF ORLANDO, FLORIDA.

HAND TRUCK.

Application filed August 8, 1927. Serial No. 211,451.

The invention relates to hand trucks particularly adapted for handling boxes of fruit at packing plants, but applicable for general use, and has for its object to provide a device 5 of this character having means for gripping the opposite sides of an article and holding the same, thereby allowing stacks of boxes to be easily moved from place to place and to be deposited on the floor in close engagement 10 with adjacent stacks.

A further object is to provide the lower end of the truck with outwardly extending slide- 15 able bars, the outer ends of which terminate in adjustable forwardly extending arms 15 adapted to grip opposite sides of an article, for instance a box, and foot lever control mechanism cooperating with said bars, whereby said bars can be moved inwardly towards each other for forcing the gripping 20 arms into close binding engagement with opposite sides of the box.

A further object is to control the slide- 25 able bars by means of pivoted levers pivoted to the frame and to the bars and having their upper ends provided with bearing members disposed in arcuate cam slots of a vertically 30 movable member, which vertically movable member, when moved in one direction forces the slideable bars inwardly to gripping position, and when moved in the opposite direction forces the slideable bars outwardly to released 35 position, and also provide the ends of the cam slots with recesses into which the bearing members of the pivoted levers engage 40 when the cam member is in locked position, thereby preventing movement of the cam member during the clamping operation until the same is manually released.

A further object is to interpose a spring 45 between the inner adjacent ends of the slide bars, which spring is compressed during the clamping operation, and assists in forcing the slide bars apart during the releasing operation.

A further object is to form the axle and foot lever carrying arms integral, thereby insuring a positive adjustment at all times.

A further object is to provide the ends of the slideable bars with substantially right an- 50 gularly shaped arms pivoted thereto, which arms are gripping arms and are provided with adjusting screws acting against coiled springs at the pivotal points, thereby allowing the arms, through the adjustment of the 55 screws, to be adjusted inwardly or outwardly according to the width of the boxes being

handled, whereby upon rocking of the pivoted levers by the cam slots a positive gripping will be insured.

A further object is to provide the gripping 60 arms with extension members whereby the length thereof may be varied according to the width of the boxes handled.

With the above and other objects in view the invention resides in the combination and 65 arrangement of parts as hereinafter set forth, shown in the drawings, described and claimed, it being understood that changes in the precise embodiment of the invention may be made within the scope of what is claimed 70 without departing from the spirit of the invention.

In the drawings:—

Figure 1 is a rear elevation of the truck, showing the mechanism in gripping position. 75

Figure 2 is a side elevation of the truck.

Figure 3 is a perspective view of one of the gripping arms.

Figure 4 is a horizontal sectional view 80 through one of the gripping arms.

Figure 5 is a horizontal sectional view through the lower end of the truck taken on line 5—5 of Figure 2.

Figure 6 is a vertical transverse sectional view through the lower end of the truck. 85

Figure 7 is a detail view in elevation of a portion of the cam member, showing the recess in the bearing member for holding the mechanism in gripped position.

Referring to the drawing, the numeral 1 90 designates the side bars of the truck, which bars are connected together by means of transversely disposed bars 2, 3, 4 and 5. Se- 95 cured to the rear sides of the bars 1 are bearing members 6 in which are mounted at 95

7 the ends of the axle 8, and on which axle are rotatably mounted ground engaging wheels 9. Extending upwardly from the axle 8 are spaced integral ears 10 between 100 which is pivotally mounted at 11 a foot lever 12. The forward end of the foot lever 12 is pivotally connected at 13 to the lower end of a vertical slide rod 14, and which slide rod is slidably mounted in bearings 15 car- 105

ried by the rear sides of the bars 3 and 4 therefore, it will be seen that when the operator places his foot on the outer end of the foot lever 12, and forces the same downwardly, the bar 14 will be forced upwardly. Con- 110 nected to the bar 14 at 16 is a cam member 17, which cam member is provided with arcu- ated cam slots 18, in which is disposed the

bearing members 19, and during the upward and downward movement of the cam member 17, said bearing members 19 are moved towards or away from each other.

6 Bearing members 19 are carried by the upper end of downwardly extending pivoted levers 20, which levers are pivotally connected at 21 to the bar 4 intermediate their ends, and have their lower ends provided with slots 22, into which pins 23, carried by the slide bars 24 engage, therefore it will be seen that as the cam member 17 is moved upwardly or downwardly, the arms 20 will be rocked on their pivotal points 21, for forcing the bars 24 inwardly or outwardly for a box gripping or releasing operation. Bars 24 are slidably mounted in bearing members 25 carried by the forward side of the bars 1, therefore it will be seen that the bars 24 will be positively guided at all times. The lower ends of the cam slots 18 are provided with recesses 26, into which the bearing members 19 engage when the mechanism is in clamped position as shown in Figure 1, and said recesses maintain the cam member 18 in raised position, and the parts in clamped position. This operation is additionally insured by means of the expansion spring 27 which is compressed when the bars 24 are in clamped position and 30 which coiled spring is mounted on the arms 28 of a plate 29 secured to the rear side of the bar 5 as clearly shown in Figure 1, consequently the clamping mechanism is locked in clamped position. When it is desired to release the mechanism, the operator may place his foot on the arm 30 carried by the bar 14 and force the same outwardly, and which operation will slightly compress the spring 27, and the expansive action of the spring and the 40 weight of the cam member 17 and rod 14 will then force the slide bars 24 outwardly to released position.

The outer ends of the slide bars 24 are provided with rearwardly extending ears 31, which ears extend into chambers 32 of the angularly shaped gripping arms 33, and which arms 33 are pivotally connected to the ears 31 by means of pins 34. Surrounding the pins 34 are coiled springs 35, one of the 50 ends of which is anchored at 36 to one of the ears 31, and the other arm 37 engages the inner side of the arm 38 of the gripping arm, thereby forcing the same outwardly at all times. The arms 39 of the gripping arms overlap the rear sides of the bars 24 and are provided with adjusting bolts 40, which cooperate with the rear sides of the slide bars 24, and form means whereby the outer ends of the gripping arms 38 may be adjusted inwardly or outwardly according to the width of boxes being handled, and the relation of the cam slots 18 thereto when the mechanism is in gripping position, therefore it will be seen that wide range of adjustability is obtained. Adjustably mounted on the arms 38

are extension arms 41 having gripping lugs 42 at their outer ends which may be welded or otherwise secured thereto. The extension arms 41 are secured to the arms 38 by means of bolts 43, which bolts extend through elongated slots 44 in the arms 38 and 41, therefore it will be seen that the extension arms 41 may be easily and quickly adjusted outwardly for increasing the length of the gripping arms according to the depth of the boxes being handled. The cam member 17 is provided with arms 45 at opposite sides of the bar 14, which cooperate with opposite sides of the bar 14, for preventing a pivotal movement of the cam member 17 at 16.

From the above it will be seen that a truck is provided with cam actuated gripping arms, which arms may be adjusted inwardly or outwardly or extended in length, and the axle and arms carried thereby to which the operating lever is pivotally connected are integrally formed, thereby insuring proper adjustment at all times and obviating the difficulty now experienced where the lever is pivotally connected to a collar secured to the axle by a set screw. It will also be seen that the device is simple in construction, positive in its operation, and the same can be cheaply manufactured and sold.

The invention having been set forth what is claimed as new and useful is:—

1. The combination with a truck, an axle carried by said truck, ground engaging wheels carried by said axle, gripping bars slidably mounted in the lower end of said truck, of means for controlling said gripping bars comprising a cam member having arcuate cam slots, a vertically movable slide bar carried by the truck and to which the cam member is connected, substantially vertically disposed rock bars pivotally connected to the truck below the cam member, bearing members carried by the rock bars and disposed in the cam slots of the cam member, the lower ends of said rock bars being connected to the gripping bars.

2. The combination with a wheel supported truck having inwardly and outwardly movable slide bars at its lower end, gripping arms carried by the outer ends of the slide bars, or means for simultaneously moving said slide bars towards or away from each other, said means comprising vertically disposed pivoted rock levers, one of the ends of said rock levers being connected to the slide bars, a vertically movable cam member having arcuate cam slots and above the pivotal points of the rock levers and anti-frictional bearing members carried by the upper ends of the rock levers and disposed in the cam slots.

3. The combination with a wheel supported truck having inwardly and outwardly movable slide bars at its lower end, gripping arms carried by the outer ends of the slide bars,

of means for simultaneously moving said slide bars towards and away from each other, said means comprising vertically disposed pivoted rock levers, one of the ends of the 5 rock levers being connected to the slide bars, a vertically movable cam member having cam slots therein and disposed above the pivotal points of the rock levers, members carried by the levers and disposed in the 10 cam slots, the lower ends of said cam slots being provided with inwardly extending recesses for the reception of the lever carried members when the cam member is in upper position during a clamping operation, and an 15 expansion spring interposed between the inner adjacent ends of the slide bars and forming means for maintaining the lever carried members in the cam recesses and lever means for controlling the vertical movement 20 of the cam member.

4. The combination with a wheel supported truck having inwardly and outwardly movable slide bars adjacent its lower end, gripping arms carried by the slide bars, of means 25 for simultaneously moving said slide bars

towards or away from each other, said means comprising upwardly extending pivoted rock levers, one of the ends of the rock levers being connected to the slide bars, means for normally forcing said slide bars apart, an upwardly extending and upwardly movable cam member having arcuate cam slots and above the pivotal points of the rock levers and members carried by the upper ends of the 30 rock levers and disposed in the cam slots. 35

5. The combination with a wheel supported truck having inwardly and outwardly movable sliding gripping bars, pivoted control levers for said gripping bars, a movable member having cam slots, members carried by the 40 levers and disposed in the cam slots, said members upon movement of the sliding member in one direction being received in recesses at the ends of the cam slots, of spring means normally forcing the gripping bars apart and 45 maintaining the lever carried members in the recesses of the cam slots.

In testimony whereof I hereunto affix my signature.

JAMES AUGUST BYINGTON.
